UNITED STATES PATENT OFFICE.

JAMES F. POCOCK, OF LANCASTER, OHIO.

TOOTHBUSH HOLDER.

Application filed November 24, 1925. Serial No. 71,253.

The present invention relates to a device for holding tooth brushes or other articles of a similar character, so that dirt, dust, and the like will be excluded from the brushes, and they will thus be kept in more sanitary condition.

In the accompanying drawings:

Figure 1 is an end elevation of the device,
Figure 2 is a rear elevation.

Figure 3 is a perspective view of the rear wall.

Figure 4 is a perspective view of the front wall or cover,

Figure 5 is a sectional view on the line 5—5 of Figure 2,

Figure 6 is a sectional view on the line 6—6 of Figure 1.

The device is made up of two principal parts, a rear wall member and a cover member. The rear wall member preferably consists of a substantially flat sheet 7 of metal, having a horizontal rearwardly pressed groove 8 in its upper portion and a pair of bearing projections 9 in its lower portion. The lower end of this sheet is outturned, preferably at a slight upward inclination, forming an integral flange 10. This flange is provided with a set of rearwardly tapered cuts or openings 11, terminating in enlarged sockets 12, the cuts thus providing a series of jaws 13 between them. In order to reinforce the flange the rear wall is furthermore preferably provided with outstanding end flanges 14 that are suitably connected to the ends of the flange 10. The rear wall is also provided with suitable openings 15 to receive fasteners, by which the device can be secured to a wall or other support.

The cover member also preferably consists of a substantially flat sheet 16, the upper end of which is formed into a loop 17 that surrounds a pintle or pivot wire 18. This loop 17 fits into the groove 8 of the rear wall and the ends of the wire pass through and are hooked about said rear wall, as indicated at 19, thus providing a pivot mounting between the upper end of the cover member and the rear wall mem-

ber. The lower edge of the cover member is preferably doubled, as shown at 20, doing away with sharp edges, and thus the doubled end or margin extends slightly below the flange 10, forming a convenient projection that can be engaged by the finger to raise the cover. The cover member also has its end portions bent rearwardly into triangular end walls 21 that close the space between the front wall and the rear wall and overlie the flanges 14.

It will be evident that with this construction tooth brushes may be placed in the sockets and removed therefrom with entire convenience, and when in place and the cover is closed the heads of the brushes are completely covered and thus protected from dust, and other unsanitary conditions. The device is extremely simple in its make-up, inasmuch as the parts can be stamped from sheet metal and readily joined.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

What I claim is:

A tooth brush holder comprising a rear wall having an integral outturned bottom flange provided with tooth brush holding means, and end flanges that are connected to the bottom flange, a cover comprising a plate hinged at its upper end directly to the upper portion of the rear wall and having its lower end overhanging the bottom flange thereof, said cover having substantially triangular end walls that extend over the ends of the bottom flange and over the end flanges and close the space between the rear wall and cover.

In testimony whereof, I affix my signature.

JAMES F. POCOCK.
